Electric Company, a corporation of New York

Filed Oct. 19, 1960, Ser. No. 63,552

3 Claims. (Cl. 333—21)

This invention relates to barriers for pressurized or evacuated waveguides. That is, the invention relates to window barrier sections which separate two regions in the waveguide or waveguide system and provide for the transmission of electromagnetic waves between the two regions.

The barriers or seals of the type under consideration are particularly useful in the input and output waveguide connections of an electron tube which operates at microwave frequencies. In such applications electromagnetic energy must be transmitted between the evacuated interior of the tube envelope and exterior waveguide systems which may be maintained at atmospheric or other pressure. Other examples of such windows are found in applications where a barrier is required to prevent the escape of gas from a pressurized system or where a barrier is required to contain a cooling or insulating fluid in a waveguide system. These barriers which are called microwave windows have taken various forms using a variety of metal and dielectric materials.

The use of microwave windows introduces a number of electrical and mechanical problems. The electrical problems include the introduction of reflections at the dielectric barrier due to the discontinuity in the medium in which the electromagnetic waves must travel, voltage breakdown in the presence of high electric and magnetic fields in the area of the dielectric barrier and the dissipation of microwave power within the dielectric material. The mechanical problems encountered include difficulty in providing a leak proof mechanical design which can withstand the elevated temperatures required for processing and operation, has the mechanical strength to maintain line dimensions at correct values and is capable of reproduction in quantity with uniformity in dimensions and properties.

The electrical problems involved may best be understood by considering a particular application for microwave windows of the type under consideration. As an example consider a window used for transmission of microwave energy from a high power source, such as a klystron, to an external waveguide system. An output window for such generators must be capable of transmitting the generated power to the waveguide system with a minimum of reflection and absorption of energy. Power absorbed at the window or reflected by the window is lost and reflected energy may severely damage the power source. Power absorption in a window of a given geometry is a function of the dielectric material and may be determined by selecting the material. Reflections in a transmission line are caused by discontinuities along the length of the line which represent abrupt discontinuities in impedance. Such discontinuities may be caused by a dielectric position in the transmission line or they may be caused by a change in the physical dimensions of the transmission line or both. The transmission line window and support structures described herein have a physical configuration which provide a good impedance match over a broad band of frequencies and thus reduce reflections to a minimum.

Among the most serious problems encountered when using microwave windows is the actual mechanical failure

2

of the barrier. For example, the vacuum seal around the dielectric barrier may fail as a result of over heating around the seal, there may be a thermal breakdown resulting in decomposition of the dielectric material at high levels of average power due to power dissipation in the window or there may be a cracking or puncture of the dielectric material from arcing or non-uniform heating in the region of the barrier. Such failures can generally be attributed to electrical phenomena. That is, they are generally believed to be the result of voltage gradients due to the electric and magnetic field configuration in the area of the windows.

Accordingly it is the object of the present invention to provide a microwave transmission and window section having a structure which provides electric and magnetic field configurations in the area of the window that tend to increase the power handling capability of the section and minimize the problems of arcing, thermal breakdown, cracking, punctures, and other failures in the regions of the dielectric barrier.

Although the mechanical problems involved in microwave window design are easier to understand than the electrical problems they are no less important. For example, if the design of the window and its associated support is not such as to permit a strong vacuum tight joint, the barrier is ineffective. Also if the mechanical strength of the window is not sufficient to maintain dimensions under normal operating conditions and at the elevated temperatures required for processing, the advantages of a careful design are lost. Further, unless the design is capable of production and reproduction in quantity with uniformity in dimensions and properties the usefulness is reduced considerably. The mechanical design of the window section of the present invention is particularly effective in that it does provide a barrier which separates two regions in the transmission line system, presents a simple strong vacuum tight mechanical structure and produces a minimum of reflection over a wide band of frequencies.

Briefly stated, in accordance with this invention a microwave window and transition section is formed by converting incident microwave energy into the circular transverse electric waveguide mode which has electric field lines that are circular and concentric throughout the length of the waveguide before the microwave energy passes through the dielectric barrier of the window section and providing a structure for the section which presents complete electrical and mechanical symmetry to the incident electromagnetic waves. The circular waveguide mode referred to is usually designated as the TE_{01} mode. Thus, the circular TE_{01} mode is one where there is no radial component of electric field in the waveguide and the circular component has no variation with respect to the angular coordinate.

The novel features which are believed to be characteristic of the invention are set forth in the appended claims. The invention itself, however, both as to its organization and method of operation together with other objects and advantages may best be understood by reference to the following description taken in connection with the accompanying drawings in which:

FIGURE 1 is a partially broken away central vertical longitudinal section taken through a portion of a window section illustrating a particular type of mode launcher which may be used;

FIGURE 2 is a partially broken away perspective view of the window section of FIGURE 1;

FIGURE 3 is a partially broken away exploded perspective view showing a window section using a barrier support section similar to that of FIGURES 1 and 2 but a different mode launcher;

FIGURES 4 and 6 are central vertical longitudinal sections taken through portions of window sections or barrier supports which may be utilized with the present invention; and

FIGURE 5 is a partially broken away transverse section taken through a tubular body portion of the window support section of FIGURE 4.

Referring specifically to FIGURES 1 and 2 of the drawings a portion of a window section 10 constructed in accordance with the present invention is seen. For simplicity only a portion of the window section 10 is illustrated and the systems joined by the window section are omitted. As illustrated the window section includes a cylindrical pipe-like window-supporting section or structure 11 and a mode launcher section 12 designed to launch the circular transverse electric mode designated as the TE_{01} mode in the circular waveguide section 11. As illustrated, the circular waveguide window-supporting section 11 is in effect closed at opposite ends by circular conductive end walls 13 which are provided with apertures 14 (described in detail subsequently) for admission and extraction of electromagnetic energy. In order to provide a pressure barrier in the window-supporting section 11 a flat dielectric disc 15 is positioned mid-way between the end walls 13 which close the cylindrical supporting section 11. The dielectric disc 15 is sealed in vacuum tight relation around its outer periphery to the inner circumference of the cylindrical section 11. In the embodiment illustrated, the dielectric barrier 15 is positioned between two inwardly projecting conductive flanges 16 and 17 which are designed to produce an electrical reflection which adds to that produced by the dielectric slab 15 in such a way as to balance out reflections in the window section 10. The length of the cylindrical supporting section on either side of the dielectric barrier 15 (from end wall 13 to dielectric barrier 15) is approximately one half wave length for the TE_{01} mode at the frequency of interest.

It is believed that the construction of a cylindrical window-supporting section 11 such as the one illustrated is well within the skill of one versed in the art. However, in the interest of completeness it is noted that the section illustrated is made up of two circular waveguides 18 and 19 each having one of the conductive end plates 13 brazed at one end and having their open ends brazed together to form a continuous cylindrical section.

The conductive reflective window supporting flanges 16 and 17 are formed on the two circular waveguides 18 and 19 respectively. That is, the conductive flange 17 on one side of the window projects inwardly from the open end of circular waveguide section 19 and the other conductive window supporting flange projects inwardly from the other circular waveguide section 18 around a circumference which is displaced from its open end by a distance which corresponds to the thickness of the dielectric barrier or slab 15. Thus, the barrier 15 may be placed in position and the ends of the two circular waveguide sections 18 and 19 brought together and brazed to form the unitary cylindrical window-supporting section 11.

As previously indicated the end plates 13 which essentially close opposite ends of the cylindrical window supporting section 11 are each provided with a pair of rectangular apertures 14. These apertures are located to launch or excite the transverse electric TE_{01} circular waveguide mode in the cylindrical window-supporting section 11. In order to accomplish this, the apertures 14 are symmetrically located on opposite sides of the center of the discs or plates 13. In other words the rectangular apertures are bisected by a diameter of the circle defined by the end closing plates 13 and are symmetrically located equidistant on opposite sides of a diameter which is perpendicular to the bisecting diameters. The broad dimensions of the rectangular apertures extend outwardly from the center of the end closing plates parallel to the bisecting diameter.

In the embodiment of FIGURES 1 and 2 the mode launching section 12 which introduces electromagnetic waves in the window-supporting section 11 to excite the desired TE_{01} mode consists of two rectangular waveguides 20 and 21 which form a structure described in the art as a folded, E-plane, T. The structure is designed to divide electromagnetic energy carried by the single input rectangular waveguide 20 into two equal components which energy may be recombined in the circular partly resonant window-supporting section 11 in such a way as to excite the desired circular TE_{01} mode.

An inspection of the mode launcher or transformer 12 illustrated will show that the name used in the art is descriptive. That is to say that the structure of the mode launcher 12 resembles a T. The input rectangular waveguide 20 forms the upright of the T and the power dividing rectangular waveguide 21 forms the upper cross-bar of the T. The upright waveguide 20 extends into one broad wall of the power dividing cross-bar waveguide 21 with its broad walls extending across the broad wall of the cross-bar. Thus, as illustrated, input power introduced in the lower part of the upright waveguide 20 enters the power dividing cross-bar waveguide 20 and is divided evenly so that part of the power goes in one direction and part of the power goes in the opposite direction. The cross-bar waveguide 21 is bent around a narrow wall (an H plane bend) essentially over the upright waveguide to define a U-shape. The ends of the U-shaped cross-bar waveguide 21 extend back and fit in the apertures or slots 14 of one of the end plates 13 of the window supporting structure 11. Thus, the power which enters the upright waveguide 20 is divided and introduced in the cylindrical window supporting section 11 in the proper phase to excite the circular TE_{01} mode. The particular mode exciter illustrated has the property of exciting only modes in which the first index digit is even and does not excite odd modes such as the TE_{11} mode which might otherwise be troublesome.

Because it is rarely practical under the present art conditions to consume the output power in the form of the TE_{01} circular waveguide mode it is ordinarily necessary to reconvert to one or more rectangular waveguides. In the embodiment of the window section illustrated it is contemplated that the reconversion will take place by means of a mode converter output section which is identical to the input mode converter previously described. Therefore in order to simplify the drawings and description the output mode converter is not illustrated in detail. Electrical reflections inevitably result from the discontinuity at the dielectric barriers. Likewise reflections will occur at one or more points within the associated launching structure. However, by carefully choosing the dimensions of the structure including the radial width of the metallic flanges on the opposite sides of the dielectric barrier, excellent operation is obtained over frequency bands of the order of 20%. That is over a band of frequencies which is 20% of the center frequency for which the device is designed. For example, if the center frequency of the range of interest is 2500 megacycles per second the bandwidth would be on the order of 500 megacycles per second extending approximately from 2250 megacycles per second to 2750 megacycles per second.

An inspection of the window section 10 shows that the dielectric barrier and its supporting structure has complete circular symmetry with respect to both electrical and mechanical properties. This is important because many window failures are traceable to non-uniform electric fields and non-uniform heating resulting in undesirable stress concentration. Further, the conversion of the energy incident on the dielectric barrier to the TE_{01} circular mode eliminates longitudinal current flow in the cylindrical waveguide. Thus, with respect to the desired circular electric fields a slot into which the dielectric window is fitted (the slot formed by the metallic flanges 16 and 17 on op-

posite sides of the window 15) acts as a strongly attenuating waveguide below cut-off, so that only very small currents flow around the perimeter of the dielectric barrier. This fact is important because all known techniques for making ceramic to metal seals result in a bond which is a relatively poor conductor and therefore subject to excessive heating when subjected to large values of current.

Since the TE_{01} circular waveguide mode is utilized in the cylindrical window-supporting waveguide section 11 the electric field is everywhere tangential to the surface of the dielectric and is substantially weaker than the field associated with the same amount of power in the normal rectangular waveguide. For example, the relation of power to maximum field in the normal rectangular waveguide is given by the equation:

$$P/E^2 = 8.3 \times 10^{-5} \gamma_c^2 \times \sqrt{1 - (\gamma/\gamma_c)^2}$$

γ is the operating wavelength, γ_c is the cut-off wavelength, and where the small dimension of the rectangular waveguide is half the larger one. The corresponding relations for the TE_{01} mode in circular waveguide is:

$$P/E^2 = 7.4 \times 10^{-4} \gamma_c^2 \times \sqrt{1 - (\gamma/\gamma_c)^2}$$

For specified values of γ , γ_c and E , the power handling capacity of the circular guide is 9 times greater than that of the rectangular guide. This difference is most important in the gaseous region just outside the dielectric window.

An additional factor of importance is that no component of the electric field is normal to the metal surface in the region of the dielectric 15, therefore, roughness, surface emission, multipactor discharge, and other such effects do not reduce power handling capacity. The fact that the electric field is everywhere tangential to the dielectric barrier leads to the desirable situation that there is no discontinuity of field value and no flux concentration in this region.

FIGURE 3 illustrates the same type of window supporting section 11 as that illustrated in FIGURES 1 and 2 and described above. However, the window-supporting section 11 is utilized with a slightly different kind of mode converter which also excites the TE_{01} circular waveguide mode in the window section 11. This mode launcher may be considered an E-plane power divider terminated by a shorting plane. In view of this fact that the window support section 11 is almost identical to that of FIGURES 1 and 2 corresponding parts of the two devices are given corresponding reference numerals and this part of the window section is not again described in detail. The only difference in the window support sections of the two embodiments is found in the end plates 13 which essentially close the opposite ends of the sections 11. Each of the end plates 13 of the embodiment of FIGURE 3 is provided with four power transfer apertures 24 (2 pairs of apertures) instead of the two apertures 14 (one pair) utilized with the end plates 13 in FIGURES 1 and 2. These apertures 24 are provided to accommodate the different type of mode launcher of this embodiment. The apertures 24 are again rectangular slots positioned radially in the end plates 13. However, each pair of radial slots is bisected by a diameter which is displaced 90° from the other pair. In other words the mode launcher 25 illustrated in FIGURE 3 utilizes four symmetrically disposed feeds instead of the two feeds utilized in the symmetrical mode launcher of FIGURES 1 and 2.

The mode launcher 25 is composed of a rectangular input waveguide 26 which divides into two similar parallel waveguides 27 and 28 so that the electromagnetic energy in the input waveguide 26 is equally divided. As illustrated, division of the input rectangular waveguide 26 is accomplished by tapering the broad walls 29 and 30 outwardly (spread them apart) and in effect inserting another broad wall septum 31 between the existing broad walls.

In this manner the two parallel power dividing rectangular waveguides 27 and 28 are formed. These waveguides have approximately the same internal dimensions as the input rectangular waveguide 26. The ends of the two power dividing rectangular waveguides 27 and 28 are closed by a rectangular conductive end closing plate 32 which may be brazed in place to form a vacuum tight closure if necessary. Also the power dividing waveguides may be terminated by any of the common means known in the art if reflections of incident power become a problem.

A circular aperture 33 is provided in the upper wall of the mode launching structure 25 to receive one end closing plate 13 of the window supporting section 11. The circular aperture 33 is bisected by the central broad wall 31 of the mode launching structure 25. In other words, half of the aperture 33 extends over each of the power divider rectangular waveguides 27 and 28. In order to provide for the proper mode excitation in the window-supporting section 11 and the best power transfer from the mode launcher 25, one end plate 13 (the lower one) is positioned in the aperture 33 with all of the four power transfer apertures 24 located equidistant from the central broad wall 31. Thus, one slot or aperture 24 of each pair of apertures in the end plate 13 is open to one of the rectangular waveguides 27 and 28. In this manner power in the input rectangular waveguide 26 divides equally in the two power dividing or launching waveguides 27 and 28 and excites the circular TE_{01} mode in the cylindrical window-supporting section 11. The end plate 13 is preferably sealed in the circular aperture 33 to provide a vacuum tight closure.

The window section of FIGURE 3 has the same advantages as the window section of FIGURES 1 and 2. For a more complete discussion of the particular type of mode launcher of FIGURE 3 reference may be had to The Transactions of the IRE, Professional Group on Microwave Theory and Techniques, vol. MTT 2-#2, July 1954, in the article entitled "H₀₁ Mode Circular Waveguide Components," by T. A. Lanciani, pages 45 to 51.

Other embodiments of the window or barrier supporting sections which are attractive for certain applications are illustrated in FIGURES 4 and 5 and FIGURE 6. It is intended that these structures be used with TE_{01} circular mode launchers in a fashion similar to that described in connection with previous embodiments. Therefore, the figures are broken away and do not show mode launchers or end plates.

The cylindrical window-supporting section 40 illustrated in FIGURES 4 and 5 also utilizes a flat dielectric disc 41 as the window or barrier. However, the slot 42 in which the window 41 fits in this embodiment extends outwardly from the circular waveguide body of the window section. As illustrated this window-supporting section 40 is formed by utilizing one circular waveguide 43 (left in figure) having an outwardly extending flange 44 which in turn has a forwardly extending lip 45. Thus, the lip 45 is cylindrical like the waveguide 43 and is concentric therewith but of a larger diameter. The structure thus formed provides a seat which holds the outer periphery of the dielectric disc or window 41. The mating circular waveguide 46 which makes up the remainder of the cylindrical body of the barrier supporting section 40 has an outwardly extending flange 47 formed around its outer periphery. This flange 47 butts against the outer edge of the lip 45 and the assembly is held together by some means such as a braze. Such a braze may provide a vacuum tight seal between the two circular waveguides 43 and 46 and also seal the periphery of the dielectric window 41 in its slot to form a vacuum tight barrier. In connection with forming such joints it should be noted that the outer periphery of the dielectric discs or barriers are usually metallized or otherwise treated so as to adhere to the conducting surfaces of the waveguide when the brazes are formed. The slot

in which the window 41 is seated performs the same function as described in connection with the previous embodiments.

A slightly different embodiment of barrier 50 and barrier supporting structure 51 is illustrated in FIGURE 6. In this embodiment the inner diameter of the two circular waveguides 52 and 53 on opposite sides of the barrier 50 differ. However, this is not essential to the use of the type of barrier 50 disclosed in connection with this embodiment. In this embodiment the barrier 50 is curved rather than plane. The spherical surface illustrated is attractive because it is readily generated, controlled, and measured. However, other shapes such as cones may be desirable for certain applications. The advantage of the curved surface is that the electrical reflection due to the dielectric is considerably reduced and the mechanical strength is greatly enhanced particularly if the convex surface of the window 50 is directed toward the pressurized side. As illustrated, the diameter of the circular waveguide 52 on the concave side of the barrier 50 is smaller than the circular waveguide 53 on the convex side of the barrier 50. The waveguides 52 and 53 are provided with abutting flanges 54 and 55, respectively, which are intended to butt against each other and provide a means of brazing the two waveguides together. Since the waveguides 52 and 53 have different diameters the flange 54 on the smaller waveguide 52 extends outwardly and its butting flange 55 extends inwardly on the opposite waveguide 53.

The flanges 54 and 55 are shaped so that the outer periphery of the dielectric barrier is held captive in a slot between the flanges 54 and 55 when the two waveguides 52 and 53 are held together. As in the previous embodiments the outer periphery of the dielectric barrier 50 may be metallized for brazing and the assembly may be brazed together in such a manner as to form a vacuum tight seal between the waveguides 52 and 53 and internally between the circular waveguide and the dielectric barrier 50.

FIGURE 6 has the added virtue that the pressurized side has a larger area, therefore lower electric fields than does the vacuum side. Since gas tends to break down at lower fields than may be readily supported in vacuum this leads to a well balanced design which is economical of materials and space.

While particular embodiments of the invention have been illustrated and described it will, of course, be understood that the invention is not limited to these embodiments since many modifications may be made in the circuit arrangements and the structures employed. It is contemplated that the appended claims will cover any such modifications as fall within the true spirit and scope of the invention.

What I claim is new and desire to secure by Letters Patent of the United States is:

1. A waveguide window section including in combination a window supporting section and a mode launching means connected to said window supporting section; said window supporting section including a cylindrical waveguide of circular cross section and a dielectric barrier supported within said window supporting section and sealed therein to provide a vacuum tight barrier, and circular conductive end closing members for closing the opposite ends of said cylindrical waveguide, each of said end closing members being provided with a pair of rectangular apertures symmetrically disposed on opposite sides of the center thereof with their major axes on a common diameter, said mode launching means comprising waveguides of rectangular cross section defining a folded E plane T with the ends of the rectangular waveguide which forms the cross bar of the T inserted in the rectangular apertures of one conductive end plate thereby to launch the circular TE₀₁ mode in said window supporting section.

2. A waveguide window section comprising: a cylindrical waveguide of circular cross section; a dielectric barrier supported within said waveguide and sealed thereto to provide a vacuum tight barrier; a circular conductive end member for closing one end of said waveguide, said end member being provided with a pair of apertures therethrough, said apertures being disposed on opposite sides of the center of said end member; a first rectangular waveguide section bent around a narrow wall thereof to define a U-shaped structure wherein the broad walls of said first rectangular waveguide section lie in respective parallel planes, the ends of said first waveguide section being joined to said end member to couple electromagnetic energy to respective ones of said apertures, and wherein one of said broad walls is provided with an opening therethrough; and a second rectangular waveguide section, said second section being joined to said one broad wall of said first section to couple electromagnetic energy to said opening; whereby electromagnetic energy in said second rectangular waveguide section is transmitted through said first rectangular waveguide section to launch the circular TE₀₁ mode in said cylindrical waveguide.

3. The waveguide window section of claim 2, wherein said apertures are rectangular in shape.
